UNIVERSAL GAS VALVE

Isaac V. Brumbaugh, Clayton, Mo.

Application August 23, 1955, Serial No. 530,123

4 Claims. (Cl. 137—614.17)

This invention relates to improved valves and, particularly, to gas valves that are adjustable to a wide variety of fluids and pressures. These valves are particularly useful to control the burners of kitchen ranges, but it is to be understood that they are adaptable to many other uses.

In the manufacture and use of gas appliances, there has long existed a need for adjustable valves that can be used universally and, regardless of the source, pressure, and type of inflammable fluid used, provide a predetermined heat for a given setting of the valve handle. The valves in today's kitchen ranges commonly have no markings. These valves typically consist of a simple inlet and outlet and a plug having a single passage therethrough positioned within the casing and adapted at times to connect the inlet opening with the outlet opening. Adjustment or "turn-down" of the flame is accomplished by partial closing or constriction of the passageway by the process of turning the plug so that the passage through it is displaced slightly out of registration with the ports in the casing. When installed in different communities where gas pressures vary and the type of combustible gas available is different, a wide variety of flames are obtained for any particular setting of the valve handle. Similarly, when using the conventional valve, the flame cannot be accurately controlled. When turning the handle of conventional valves, a more-or-less constant flame is obtained until the handle has been turned about 170 degrees of rotation; between 170 and 200 degrees, nearly full pressure is obtained. Thus, the flame goes from near-simmer to full-on in a relatively slight turn of the handle. As a result, it is nearly impossible to obtain even approximately the same flame each time the valve is set, which is a great inconvenience when preparing food on a kitchen range.

In U.S. Patents 2,626,160, 2,650,610, 2,650,612, and 2,650,613, valves are disclosed in which the gas may not only be turned on and off, but also the size of the flame may be varied uniformly as the valve is rotated between the "off" and "on" positions. These valves may have dial knobs on which various numbers are placed and thus for a given setting of the valve handle the flame provides a predetermined amount of heat. They are also adjustable so that the valve may be adjusted in accordance with the source of the fluid available, and for a given setting of the valve handle the valve may be adjusted to provide a predetermined amount of heat regardless of the source of fluid.

It has been found that by means of the valves of the present invention, improved accuracy and adjustability may be attained over the valves disclosed in the above-identified patents.

The valves of the present invention are made of parts that are easily reproducible by today's production methods, and are easily assembled and adjusted. They are much less susceptible to incorrect assembly and adjustment than the prior-art valve. These valves accurately control the size of a flame, as it is varied uniformly between the "on" and "off" positions. They are also

2

adjustable so that for a given setting of the valve handle the valve may be adjusted to provide a predetermined amount of heat, regardless of the source of gas.

The valves of the present invention are generally characterized by the metering effect of a tapered port which is opened or closed to the flow of fluid by the longitudinal movement of a sleeve. Specifically, the following are embodiments of the present valves:

Positioned in a valve casing which is provided with 10 inlet and outlet ports is a hollow, rotatable valve plug provided with an elongated slot, which cooperates with the inlet port when rotated, to allow fluid to flow into the valve. Also positioned within the casing is a hollow cuplike sleeve, formed with a tapered port. The sleeve is 15 partially telescoped into the plug and is threaded to a screw attached to the plug, but is keyed to the casing so that it does not rotate with the plug. The sleeve thus moves longitudinally in accordance with the pitch of the threads which attach the sleeve to the rotating plug. 20 This motion adjusts an opening created by the tapered port so that the rear edge of the plug increases or decreases the area through which gas passes, and thus meters the gas in accordance with the position of the sleeve relative to the plug. Means are also provided to 25 vary the longitudinal position of the sleeve relative to the plug, so that the flame for the simmer-position and for the other positions may be adjusted to compensate for gases of different heating values. This is accomplished by adjusting the longitudinal positions of the screw, which 30 is connected to the sleeve, and which rotates with the plug and provides the longitudinal movement of the sleeve when turning the valve. In one embodiment, this screw is attached to the plug by another screw which slips through an opening in the head of the main screw, and is 35 threaded in the plug. A spring about the head of this screw exerts pressure on the head of the main screw, pushing it forward in the valve, but allows the main screw some leeway to move longitudinally. A third screw 40 angularly positioned and extending through the plug, exerts pressure to force the main screw toward the rear of the valve. Thus, an adjustment of the angularly positioned screw adjusts the position of the main screw and the sleeve in either direction longitudinally which adjusts the opening created by the tapered port and the rear edge 45 of the plug for a given setting of the valve.

In another embodiment, the hollow sleeve contains a threaded projection extending forwardly from the center of the sleeve and threaded into the end of a rod which is positioned concentrically through the plug. The rod 50 rotates with the plug, thus effecting longitudinal movement of the sleeve, as described above. A longitudinal adjustment of the concentric rod, by turning, adjusts the longitudinal position of the sleeve, so that the flame can be adjusted to a given heat for any setting of the knob.

In the embodiments mentioned above, a metering effect is accomplished by restricting or widening the area of tapered port through which the fluid must pass. The area of the tapered port available for fluid flow is determined by the longitudinal position of a tube or cup-shaped member and the longitudinal movement of this member is accomplished by rotational movement of a threaded area. It should be noted that in each case the port is so placed that the most restricted or pointed area is the last to be covered by the longitudinal movement of the sleeve or tube in turning off the valve. Only the pit or smallest portion is exposed when the knob is set at the "simmer" position.

The primary object of this invention is, therefore, to provide a gas valve that will vary the flow of gas uniformly as the valve is rotated between the "off" and "on" position.

Another object is to provide a gas valve which can

be adjusted so that for a given setting of the valve handle the flame provides a predetermined amount of heat.

Another object is to provide a valve in which relatively large numbers of predetermined heat-rendering flames are selectively possible.

A further object is the provision of a valve which contains relatively few parts and which is relatively easy to assemble, manufacture, and adjust.

Still another object is to provide a valve which operates on the principle of a tapered port in a sleeve, capable of longitudinal movement effected by the pitch of a threaded area, to open or close the area available for fluid flow, by cooperation with a longitudinally stationary member.

Another object is to provide a valve which operates on the principle of a tapered port in a sleeve which cooperates with another member to open or close the area available for fluid flow by longitudinal movement effected by the pitch of a threaded area, in which the position of the longitudinally movable member can be further adjusted longitudinally so as to change the area available for fluid flow at any setting of the valve knob.

Further objects and advantageous features are apparent from the following specification and claims.

In the drawings:

Fig. 1 is a longitudinal sectional view of the valve;

Fig. 2 is a view in vertical section of the forward end of sleeve 26 taken at right angles to the section of Fig. 1 at the line 2—2 thereof;

Fig. 3 is a view in elevation of the sleeve of the valve of Fig. 1;

Fig. 4 is a view in vertical section of the rear end of sleeve 26 taken at right angles to the section of Fig. 1 at the line 4—4 thereof;

Fig. 5 is a view of the plug in elevation of the valve of Fig. 1;

Fig. 6 is a cross-sectional view of the plug taken on the line 6—6 of Fig. 5; and

Fig. 7 is a longitudinal sectional view similar to Fig. 1 showing an alternative form of the valve.

Referring to Fig. 1, a hollow valve casing 11 has an inlet port 12 and an outlet port 13. The inlet port 12 enters through a downwardly extending inlet boss 14 which may be connected to an inlet gas manifold (not shown). The outlet port 13 enters into a threaded projection or nozzle 15 onto which is threaded an orifice cap 16 which preferably extends into a mixing tube (not shown).

The valve is provided with a spring-cap 17 forming a casing or cover over the forward portion of the valve. Within the case 11 is a plug member 18 having a stem 19 which extends forwardly through the spring cap 17 and on which is a removably secured knob or dial member 20. Associated with the stem 19 is a stop sleeve 21 which has a projection 22 which cooperates with a shelf 23 projecting from the spring cap 17 to limit the movement of the knob 20. Thus, the stem 19 and the plug 18 may not be turned beyond the "off" position when rotated in a counterclockwise direction or the "on" position when rotated in the clockwise direction. The spring cap 17 is bolted to the casing 11 in any conventional manner. Stem 19 is not perfectly round in vertical section and stop sleeve 21 is made to slip snugly around stem 19 so that it must turn with the stem. Also, knob 20 fits snugly onto stem 19 and thus stem 19 and plug 18 must rotate when knob 20 is removed.

The plug member 18 is hollow as at 24 and houses within the hollow space 24 a screw 25, the head of which is located in the forward portion of the plug 18 and the threaded portion of which projects rearwardly through the plug. Also, within the hollow of casing 11 and telescoping into plug 18 is a cup-shaped sleeve 26. This sleeve member 26 has a center portion 27 projecting forwardly into the hollow of the sleeve and con-

tains a threaded area into which the screw 25 is threaded. The sleeve also contains a key or projection 28 extending rearwardly in the valve which fits into a stationary slotted member 29. This may be seen more clearly by referring to Figs. 3 and 4. The screw 25 is resiliently held in position by an off centered screw 30, threaded into the plug 18 and extending through an off-center opening in the head of screw 25. A spring 31 bears on the head of screw 25 and at its opposite end on the head of screw 30. Bearing on the other side of the head of screw 25 is an obliquely extending adjustment screw 32 threaded through the head of plug 18. It will be noted that this adjustment screw is wholly within the spring cap 17. The adjustment screw 32 acting on screw 25 positions the sleeve 26 as may be desired, since spring 31 maintains screw 25 always in contact with screw 32. Positioned around stem 19 of plug 18 is a spring 33. The spring 33 maintains the stop sleeve 21 and the plug 18 in correct position.

Referring to Figs. 1, 5 and 6, the plug 18 is formed with a slot 34 which in certain positions communicates with inlet port 12 which, as is explained in more detail below, allows gas to pass into the hollow of the valve. Referring to Fig. 6, a slot 35, as explained below, acts as a bypass when the plug is rotated to a certain position.

Referring to Figs. 1, 3, and 5, the sleeve 26 is formed with a tapered port 36. The sleeve 26 is partially telescoped into plug 18 so that a portion of port 36 is exposed to void 37. Key 28 is loosely projected into the slot 38, which is also port 13, with sufficient room for fluid to pass around it. Sleeve 26 is free to move longitudinally; however, key 28 prevents rotation of sleeve 26. As can be seen in Figs. 3 and 5, the narrow end of the tapered port 36 projects beyond plug 18 in accordance with the longitudinal position of the sleeve 26.

The operation of the valve in Fig. 1 will be obvious from the description of the valve as shown in Fig. 1 in the full "on" position. Slot 35 communicates with inlet port 12 so that fluid may pass freely into the open area of casing 11 bypassing sleeve 26 and into area 37. From area 37 it may pass freely through slot 38 around key 28 and through orifice cap 16 into a mixing tube and thence to the burner. If the valve is turned counterclockwise so that plug 18 and thus stem 19 and sleeve 21 are rotated until projection 22 contacts stop 23, the valve is in the "off" position. In this position, neither slot 35 nor elongated slot 34 communicates with inlet port 12 and no fluid may pass into plug 18, sleeve 26, or void 37. Also, screw 25 has rotated with the plug while sleeve 26 has been prevented from rotating by key 28 and slot 38 and has thus moved longitudinally forward due to the action of the threading of screw 25 into the threaded projection 27 of sleeve 26. The movement of sleeve 26 forward in the valve has closed off the area of port 36 projecting beyond the rearward edge of plug 18. If the knob 20 is rotated clockwise to the position marked on the knob for the smallest or "simmer" flame at the burner, at least a part of elongated slot 34 communicates with inlet port 12 so as to allow fluid to pass from port 12 through slot 34 into plug 18 and sleeve 26. Due to the rotation of screw 25 in a clockwise direction, sleeve 26 has moved a short distance longitudinally rearwardly in the valve so as to extend a small portion of port 36 beyond the rear edge of plug 18. A small amount of fluid is thus metered out of the exposed area of port 36 into void 37 and thus through slot 38, orifice 16 and on to the burner.

The valve in this position may then be adjusted by turning screw 32 to move screw 25 longitudinally and thus sleeve 26 longitudinally. If screw 32 is retracted screw 25 and sleeve 26 will be displaced forwardly due to the forward pressure on the head of screw 25 exerted by spring 31 around the screw 30. If screw 32 is turned to push the head of screw 25 against the pressure of spring

31, screw 25 and sleeve 26 will be displaced rearwardly. Adjustment of screw 32 determines exactly the area of port 36 extending beyond plug 18 by the longitudinal movement of sleeve 26. Thus, for a given setting of knob 20 is a desired heat-rendering flame in simmer position may be obtained by the proper adjustment of screw 32 regardless of the fluid source.

As knob 20, and thus stem 19 and plug 18, are further rotated in a clockwise direction to various predetermined positions on the knob, it can be seen that slot 34 will continue to cooperate with inlet 12 so as to allow gas to flow into plug 18 and sleeve 26. Also, any further clockwise movement of knob 20 and plug 18 from the simmer position causes further rearward longitudinal movement of sleeve 26 and thus an increase of open area of port 36 through which fluid will flow. Thus, for each position of the knob nearer to the "on" position, a correspondingly larger burner flame is provided. The adjustment of the "simmer" position of knob 20 to a desired predetermined heat-rendering flame effects each position of the knob in that a correspondingly larger or smaller area of port 36 is available at each position so that one adjustment of the simmer flame provides equivalent standard heat-rendering flames for each of the other predetermined positions on knob 20. It is of course obvious that the adjustment of the burner flame could be made at any given setting of the knob and other positions should then render desired predetermined heat-rendering flames regardless of the source of gas.

When the valve approaches and is in the full "on" position, both void 35 and slot 34 may cooperate with inlet 12 so that there is no position of the plug in this area in which gas is prevented from flowing from inlet 12 into void 24. In fact, both void 35 and slot 34 may cooperate with inlet 12 when the knob is in the full "on" position, the purpose of slot 35 being to assure a maximum flow of fluid through the valve.

In the modified embodiment shown in Fig. 7, the valve casing 41 has an inlet port 42 which enters through a boss 44 which may be connected to a gas manifold (not shown) and an outlet port 43 which leads into a threaded projection 45 and thence to an orifice cap (not shown) which extends into a mixing tube (not shown). The valve is provided with a spring cap 47 covering the forward part of the valve. The plug 48 is provided with a stem 49 extending forwardly through the spring cap 47. A knob (not shown) fits snugly over stem 49. Stop sleeve 51 fits snugly around stem 49 so as to rotate with stem 49 and plug 48 until projection 52 of stop sleeve 51 comes into contact with a shelf 53 which is formed with spring cap 47. Thus, stem 49 and plug 48 may not be turned beyond the "off" position of the valve when rotated in a counterclockwise direction or the "on" position when rotated in the other direction. Spring cap 47 is bolted to casing 41 in any conventional manner. Plug 48 is hollow as at 54 and is formed with a longitudinal axial bore through which the relatively long screw 55 extends. Screw 55 is formed with a projection 46 which extends rearwardly into the hollow of the plug 48 or void 54. Projection 46 is provided with a threaded receptacle 69. Screw 55 projects forwardly through and beyond stem 49 and is threaded at 60. Nut 61 is threaded to screw 55 at 60 and screw 55 may be tightly secured to stem 49 by tightening nut 61. When nut 61 is tightened or drawn tightly to stem 49, the shoulder 50 of projection 46 of screw 55 is drawn up tightly against plug 48 so that screw 55 rotates with stem 49 and plug 48. Plug 48 is provided with an elongated slot 64 and a bypass slot 65. Stem 49 is provided with a spring 63 which bears against stop sleeve 51 and plug 48 in order to maintain the sleeve 51 and the plug 48 in spaced relationship. Partially telescoped into plug 48 and extending rearwardly therefrom is a cup-shaped sleeve 56 which is formed with a threaded projection 57 extending forwardly into the hollow of plug 75

48 and void 54 and is threaded into the threaded area 69 of projection 46 of screw 55. Sleeve 56 is formed with tapered port 66 and is also provided with a rearwardly extending key 58 which extends loosely through slot 68 of stationary slotted member 59. On the most forward end of screw 55 is a screw driver receptacle 62.

The operation of this embodiment is similar to the embodiment previously described. The threaded area of the cup-shaped sleeve 56 and the adjustable screw 55 must be reversed if the effect of rotating the knob in one direction or another is to be the same as the previous embodiment. A feature not obvious from the description of the operation of the previous embodiment is the adjustment of sleeve 56 for a standard heat-rendering flame for a given position of the knob. To adjust the flame, the knob is set at the "simmer" or any given position. The knob is removed and nut 61 is loosened. Screw 55 is then revolved. Depending, of course, upon the direction of the pitch of the threaded area of projection 57 of sleeve 56 and area 69 of projection 46 of screw 55, by revolving screw 55 in one direction sleeve 56 and thus port 66 will move forward longitudinally and if revolved in the other direction sleeve 56 and thus port 66 will move rearwardly longitudinally thus opening and closing the area of tapered port 66 available for fluid flow and adjusting the flame for any given setting of the knob.

While the above descriptions and illustrations set forth the valves of the present invention, various obvious changes and modifications can be made to each embodiment without departing from the spirit and scope of the invention.

What is claimed is:

1. A valve comprising a hollow valve casing having an inlet port and an outlet port; a nonrotative member positioned in said hollow and a rotative member also positioned in said hollow and associated with the nonrotative member, said nonrotative member and rotative member both being hollow and said hollow areas adjoining one another, the rotative member being formed with an elongated slot which at times cooperates with said inlet port to effect a flow of fluid into the hollow area of said rotative and nonrotative members, said nonrotative member partially telescoping into said rotative member, said nonrotative member being provided with a threaded recess which engages a threaded screw which is affixed to the rotative member and projects into the nonrotative member so that when the rotative member is rotated, the nonrotative member moves telescopically in relation to said rotative member, said nonrotative member being provided with a tapered port which at times lies contiguous with one edge of the rotative member, said edge providing a metering edge which cooperates with said tapered port upon said telescopic movement so as to effect a gradual adjustment of the flow of fluid out of the hollow recesses of said rotative and nonrotative members and into the outlet port, means for rotating said rotative member and separate means including a portion of said rotative member for adjustment of the longitudinal position of the nonrotative member relative to the rotative member.
2. A valve comprising: a hollow casing having an inlet port and an outlet port; a hollow rotative open-ended plug positioned within said casing, formed with an elongated slot through the side walls thereof, arranged to register with said casing inlet port at various positions of said plug; a hollow cup-shaped sleeve positioned within said casing, partially telescoped into said hollow open ended plug, having its open end facing the opposite direction of the open end of said hollow plug, keyed to said casing to prevent rotation, longitudinally movable, formed with a tapered port which cooperates with the edge of the open end of said plug; a screw positioned in said plug, rotatable with said plug and threaded to said hollow cup-shaped member, means to rotate said plug to effect longitudinal movement of said sleeve in accordance with the

pitch of said screw, said longitudinal movement effecting the position of the tapered port relative to the edge of the open end of said plug to effect a gradual adjustment of the flow of gas through said tapered port and means independent of rotation of said hollow plug for adjusting said screw for moving said sleeve longitudinally of said hollow plug to vary the longitudinal position of said tapered port to the edge of the open end of said plug, said independent means normally restraining said screw against longitudinal movement relative to said hollow plug.

3. A valve as in claim 2 wherein said independent means comprises a spring compressed between the head of said screw and a member secured to the plug for resiliently urging said screw longitudinally of said hollow of the plug and an eccentrically positioned screw fitted to said plug and bearing on the head of said screw.

4. A valve for controlling a top burner of a gas cooking range comprising a casing having an inlet port and an outlet port; a member comprising an open ended hollow rotative tapered plug formed with a slot extending through a side wall thereof at times registering with said inlet port and at such times allowing passage of gas from said inlet port to the hollow of said plug; a member comprising an open ended cup shaped sleeve having a tapered port formed in a side wall thereof, having a portion thereof threaded, and being positioned at least partially in the hollow in said plug with its open end directed toward the closed end of said plug and longitudinally slidably mounted in said plug and said casing; a second

5 threaded member positioned at least partially in the hollow of said plug and in threaded engagement with said cup shaped threaded member; means for preventing rotation of one of said threaded members relative to said casing; means responsive to rotation of the plug for rotating the other of said threaded members so as to cause the longitudinal movement of the non-rotatable threaded member; and one of said members other than said cup shaped member being formed with a metering edge which

10 cooperates with said tapered port upon said longitudinal movement to effect a gradual adjustment of the flow of gas through said tapered port; and separate means for adjusting the relative longitudinal position of said tapered port and said metering edge.
